UNITED STATES PATENT OFFICE

122,708

DESIGN FOR A HEATER

Henry W. Faulstich, Chicago, and Walter C. Lueneburg, Evanston, Ill., assignors to Tropic-Aire, Incorporated, Chicago, Ill., a corporation of Delaware

Application May 31, 1940, Serial No. 92,704

Term of patent 3½ years

To all whom it may concern:

Be it known that we, Henry W. Faulstich and Walter C. Lueneburg, citizens of the United States, residing respectively at Chicago, county of Cook, State of Illinois, and Evanston, county of Cook, State of Illinois, have invented a new, original, and ornamental Design for a Heater, of which the following is a specification, reference being had to the accompanying drawing, forming part thereof.

In the drawing:

Figure 1 is a front elevational view of a heater showing my new design,

Figure 2 is a side elevational view; and Figure 3 is a top plan view thereof.

The rear of the heater comprises a conventional opening through which air passes to the radiator.

We claim:

The ornamental design for a heater, as shown and described.

HENRY W. FAULSTICH.
WALTER C. LUENEBURG.
